UNITED STATES PATENT OFFICE.

CHARLES A. WHELAN, OF BUENA VISTA, COLORADO.

WATER-MOTOR.

952,969.

Specification of Letters Patent. Patented Mar. 22, 1910

Application filed April 1, 1909. Serial No. 487,143.

To all whom it may concern:

Be it known that I, CHARLES A. WHELAN, a citizen of the United States, residing at Buena Vista, in the county of Chaffee and 5 State of Colorado, have invented a new and useful Improvement in Water-Motors, of which the following is a specification.

My invention is an improvement in water motors, and consists in certain novel constructions and combinations of parts herein- 10 after described and claimed.

Referring to the drawings forming a part hereof—Figure 1 is a central longitudinal section through the motor. Fig. 2 is an end 15 view, and Fig. 3 is a section on the line 3—3 of Fig. 1.

The present embodiment of the invention comprises a cylindrical casing 1, having at one end, which will hereafter be designated 20 the inlet end, provided with an internal annular ring 2, whose outer face is grooved as at 3 for a purpose to be presently described, the ring being secured to the casing by screws 9. A plurality of rings 4 and 4^a are 25 secured to the inner face of the other end of the casing, which will be hereafter designated as the outlet end, by means of screws 5, and the inner faces of the rings at their 30 adjacent edges are annularly recessed as at 6 to form a race, in which is received an annular series of rollers 7. A ring 8, substantially U-shaped in cross section, is secured by one of its sides 10 to the inlet end 35 of the casing by the screws 9 and the inner face of the curved or body portion of the 40 ring is shaped to fit the outer face of the flange and the other or inner side 12 of the U-shaped ring is spaced apart from the inner faces of the ring 2 as shown in Fig. 1.

45 The motor comprises a substantially cylindrical casing 13, arranged within and concentric with the casing 1, and the outlet end of the outer face of the casing 13 engages the rollers 7, while the inlet end is provided with an external annular flange 13^a whose inner face is grooved and cooperates with the groove of the ring 2 to form a ball race; receiving an annular series of balls 11. A 50 pair of blades or vanes 14, 15, are arranged within the casing 13, as shown in Figs. 1 and 2, each of said blades being arranged diagonally of the casing, and in opposite positions, the blades forming substantially a right angle with each other, and with their 55 adjacent edges slightly overlapping, as shown at 16 in Fig. 2. Each blade is sub-

stantially straight on its free edge 17 and is provided at approximately the center thereof, and at the longitudinal center of the casing with a semi-circular recess 18, the recesses cooperating to form a free central opening. The attached edge 19, of each vane is an arc of an ellipse and is attached throughout its extent to the inner surface of the casing. A bevel gear ring is secured in 60 any suitable manner to the outer surface of the casing 13 near the outlet end of the casing, and meshes with a bevel gear wheel 21, on a shaft 22, journaled in a bearing hub 23 in the side of the casing, and a ball bearing 70 24 is arranged between the hub and the shaft.

The casing 1 with the rotor in place, is arranged in the current, or in the path of movement of the waves, with the inlet end 75 up stream. The water flowing in the direction of the arrows shown in Fig. 1 strikes the blades, and since they are arranged at an angle to the lines of force exerted by the current, they are deflected to one side, thus 80 imparting a rotation to the casing 1, which movement is transmitted by the shaft 22, to the mechanism to be operated.

It will be observed that the inlet end of the casing 13 is arranged between the balls 85 11 and the inner side of the U-shaped ring, and that the free edge of the ring 4 extends closely against the outlet end of the casing 13.

I claim—

1. A device of the class described, comprising concentric outer and inner cylindrical casings, ball bearings between the casings, a shaft journaled radially of the casings and extending through the outer casing, 95 a bevel gear wheel on the inner end of the shaft, a bevel gear ring on the inner casing meshing with the bevel gear wheel, vanes within the inner casing, said vanes being arranged on opposite sides of the casing and 100 diagonally thereto and at substantially right angles with respect to each other, said vanes having one edge secured to the inner wall of the casing, and the other free, the free edges being in substantially the same plane, 105 and each provided at its longitudinal center with a semi-circular recess, the recesses cooperating to form a central free passage through the casing.

2. A device of the class described, comprising concentric inner and outer cylindrical casings, the inner casing being jour-

naled in the outer casing, vanes on the inner surface of the inner casing, a gear ring on the outer surface thereof, a shaft journaled radially of the outer casing, and a gear wheel on the shaft meshing with the ring.

3. In a device of the class described, a rotor comprising a cylinder having open ends and internal vanes, a second cylinder

within which the first cylinder is journaled, 10 and a ring secured to the intake end of the second cylinder and having a sleeve extending in the first cylinder.

CHARLES A. WHELAN.
